CLAIM

The ornamental design for a rear sight protector for pistol.

DESCRIPTION

FIG. 1 is a front left perspective view of the rear sight protector for pistol, according to our design;

FIG. 2 is a front left perspective detailed view of the rear sight protector for pistol according to our design;

FIG. 3 is a rear left side perspective view of the rear sight protector for pistol according to our design;

FIG. 4 is a right side view of the rear sight protector for pistol according to our design;

FIG. 5 is a left view of the rear sight protector for pistol according to our design;

FIG. 6 is a front view of the rear sight protector for pistol according to our design;

FIG. 7 is a rear view of the rear sight protector for pistol according to our design; and,

FIG. 8 is a top view of the rear sight protector for pistol according to our design.

The broken lines in the Figures represent a pistol and rear sight as environment that form no part of the claimed design.
